UNITED STATES PATENT OFFICE.

WILLIAM A. BASHAW, OF WILKINSONVILLE, MASSACHUSETTS.

SHUTTLE-SPRING.

1,241,076.

Specification of Letters Patent. Patented Sept. 25, 1917.

Application filed May 25, 1917. Serial No. 170,992.

To all whom it may concern:

Be it known that I, WILLIAM A. BASHAW, a citizen of the United States, residing at Winkinsonville, in the county of Worcester 5 and State of Massachusetts, have invented a new and useful Shuttle-Spring, of which the following is a specification.

This invention relates to a shuttle spring designed to hold a weft carrier or bobbin in 10 the shuttle of an automatic loom.

Such springs are provided with a pair of weft carrier holding jaws grooved on their inner faces to receive the butt rings of the weft carriers or bobbins. Springs of this 15 general type have been previously made in many different ways, but have been subject to certain objections either for lack of durability or on account of the expense of manufacture.

It is the general object of my present invention to provide an improved shuttle spring of this type in which the cost of manufacture is reduced and the durability and utility of the spring correspondingly increased.

To this end, my invention consists of the improved type of spring hereinafter described, and also of the improved process of manufacture thereof.

The preferred form of my invention is shown in the drawings, in which—

Figure 1 is a top plan view of a shuttle with my improved shuttle spring mounted therein;

Fig. 2 is a perspective view of the blank from which my improved spring is formed;

Fig. 3 is a perspective view of the blank after certain operations have been performed thereon, and

Fig. 4 is a perspective view of a completed spring.

It has been heretofore customary to form shuttle springs from a single continuous strip of stock bent into the general form shown in Figs. 1 or 4. When this stock was of uniform thickness throughout, the necessary resilience of the jaws could only be obtained by using a relatively thin stock which did not provide the necessary stiffness in the shank portion or the necessary thickness in the grooved portions. It was found necessary to increase the stiffness by the use of

spreaders or filler pieces placed between the sides of the spring in the shank portion as the spring was assembled in the shuttle. 55 This arrangement was more or less of a make-shift, involving the expense of manufacturing and assembling a separate part, and the undesirable thinness of the grooved end portions was not remedied. 60

In my improved spring, as shown in the drawings, I use a relatively thick piece of stock 10, as shown in Fig. 2, and while in the flat condition I reduce the thickness of certain portions of the stock as shown at 11 65 and 12 in Fig. 3. The edges of the end portions may also be beveled as shown at 13 if so desired.

After the stock is thus prepared it is bent into the form shown in Fig. 4 in which the 70 shank portion is of the unreduced thickness of the original stock while the portions intermediate the shank and the end portions are of reduced thickness and of correspondingly increased resilience. After the spring 75 is thus shaped the grooves 14 are cut in the unreduced end portions.

After the springs are tempered they are then ready to be assembled in the shuttle as shown in Fig. 1, no additional spreader or 80 filler pieces being required.

I thus form a shuttle spring from a single piece of strip stock and by reducing the thickness of the stock in certain portions before bending I am enabled to provide relatively stiff portions and also relatively resilient portions positioned where needed in the finished spring.

Having thus described my invention, I do not wish to be limited to the precise details 90 herein disclosed other than as set forth in the claims.

What I claim is—

1. As an article of manufacture, a shuttle spring formed of a single continuous strip 95 of material, the shank and end portions of said spring being relatively thick and stiff, and the remaining intermediate portions being of less thickness and of greater resilience.

2. As an article of manufacture, a shuttle spring formed of a single continuous strip of material of uniform width, the shank and end portions being of the full thickness of

the stock, and the remaining intermediate portions being reduced in thickness to provide increased resilience.

3. The process of making a shuttle spring which consists in taking a piece of strip stock of uniform width and thickness, reducing the thickness of the stock at two sepa-

rated points for increased resilience, and thereafter bending the stock to the shape of a shuttle spring.

10 In testimony whereof I have hereunto affixed my signature.

WILLIAM A. BASHAW.
